Inventor
David Stewart,
By Attorney W. A. de la Roche

UNITED STATES PATENT OFFICE.

DAVID STEWART, OF GOVAN, SCOTLAND.

NUT OR PIPE WRENCH.

SPECIFICATION forming part of Letters Patent No. 730,311, dated June 9, 1903.

Application filed September 8, 1902. Serial No. 122,499. (No model.)

To all whom it may concern:

Be it known that I, DAVID STEWART, a citizen of the United Kingdom of Great Britain and Ireland, residing at 27 Thompson street, 5 Govan, county of Lanark, Scotland, temporarily sojourning in the United States of America, have invented a certain new and useful Improvement in Nut and Pipe Wrenches, of which the following is a specification, such as 10 will enable others skilled in the art to which it appertains to make and use the same.

The object of my invention is to provide a nut or pipe wrench of a simple and cheap form of construction so made that the same 15 will not easily get out of order, which may be instantly adjusted to fit any nut or pipe within wide limits of diameter, and which when placed thereon will tightly grip such nut or pipe, so as to not slip thereon.

20 Such invention consists in substance of a slide-bar forming a handle provided at one end with a working face to grip the nut or pipe, usually corrugated, which slide-bar handle is provided on the front edge with a screw-

25 thread rack; a slide-piece sliding thereon; a jaw-piece having a working face similar to the working face of the slide-bar handle, usually also corrugated, pivoted to the slide-piece; a spring normally forcing the working end of

30 the jaw-piece toward the slide-bar handle; a finely-toothed or corrugated rack-face formed on the edge of the body portion of the jaw-piece abutting against the rear of the slide-bar handle; a dog having a similarly-toothed 35 face located in the slide-bar handle adjacent to the working face coacting with the toothed face of the jaw-piece to hold the same against movement during working; a spring normally forcing the dog and jaw-piece away from the

40 handle; two cheeks forming extensions of the jaw portion of the slide-bar or handle extending back on either side of the jaw-piece to prevent side motion thereof; a worm-screw 45 revolvably mounted on a shaft, which shaft is pivoted at the end adjacent to the working jaw to the slide-piece or bracket-sleeve, so as to spring into and out of engagement with the screw-thread rack of the handle or slide-bar; a spring-catch for securing the lower

50 swinging end of such shaft in position in the bracket, so as to secure the worm in the working position in contact with the screw-thread

rack; a shoulder formed on the slide-bar or handle; a tang forming an extension of the handle below the shoulder; a collar fitting on the shoulder, provided with oppositely-located 55 spring side pieces bellying away from the edges of the tang at the center, extending nearly to the outer end of the tang; handle-pieces fashioned on the inner side so as to fit 60 into the spaces between the spring side pieces and the tang and at the end so as to fit into the collar, and a conical thimble secured upon the extreme end of the tang covering the lower end of the handle-pieces, so as to secure 65 the same and the collar in position against displacement, although it is not to be understood that the invention is necessarily limited to a device comprising at once all of the elements before enumerated, as the same consists in the particular construction of certain 70 devices and parts and the particular construction, combination, and arrangement of certain devices and parts, all as hereinafter particularly set forth in the specification and 75 pointed out in the claims.

My said invention is fully set forth in the following specification, of which the accompanying drawings form a part, wherein similar characters of reference designate like or 80 equivalent parts wherever found throughout the several views, and in which—

Figure 1 is a side view in elevation of my improved nut and pipe wrench, the position assumed by the actuating thumb-actuated 85 worm-screw when swung out of engagement with its coacting screw-thread rack on the handle-bar being shown in dotted lines. Fig. 2 is a view, on an enlarged scale, partially in section, of the head or jaw portion of the device shown in Fig. 1. Fig. 3 is a like view of the handle portion, one of the handle-pieces being removed; and Fig. 4 is an inside view of the handle-piece so removed from the device in Fig. 3. 95

Referring to the drawings, my improved wrench consists of an arm or handle-bar or slide-piece A, provided at the bottom with a tang 10, between which and the main body portion of the handle is the shoulder 11. This piece A is provided on the front edge with a screw-thread or toothed rack G, meshing with the thread of a worm-gear thumb-nut D, revolvably mounted upon a short shaft 12, piv-

oted at the lower end upon a pivot-pin 13 to the sliding piece 14 in the form of a sleeve, which fits snugly upon the handle-bar A, but so as to slide easily thereon. The handle-bar 5 A is usually of the channel-bar form shown in order to combine strength with lightness, and when of such form the sliding piece 14 is provided with inwardly-extending central portions (not shown) to fit into the channels 10 of the bar, and in all cases the same is provided with a spring-catch E of any desired form adapted to coact with the grooved top 12' of the shaft 12, so as to keep the same normally in the position shown in full lines 15 in Fig. 1, with the thumb-nut D in actuating engagement with the screw-rack of the bar A. Pivoted to the rear side of the sliding sleeve 14 is the jaw-piece I, provided with the jaw-head 15, which, like the jaw-head 16 20 of the bar A, is usually provided with the serrations or teeth shown in order to get a better hold upon the pipes or nuts to be rotated, and extending backward of the pivot-joint toward the tang end of the bar A is an 25 extension 17 of the jaw-piece I, which moves in and out of a socket formed to receive it, and the rear face of the slide-piece or sleeve 14 and the abutting face of the jaw-piece being curved to fit one another the play upon 30 the pivot-joint 18 thereof is limited to just sufficient amount to allow of adjustment easily upon the nut or pipe.

Projecting backward on either side of the jaw-piece I from either side of the jaw-head 35 16 of the bar A is a side lug 19, between which the bar of such jaw-piece plays freely in and out as swung upon the pivot-joint 18, and also playing between these two side lugs 19 is a spring-dog 20, actuated by a spiral spring 40 21, the rear face of which is provided with fine downwardly-faced serrations or teeth 22, adapted to register with coacting downwardly-faced similar teeth forming a rack 23 on the inner abutting face of the jaw-piece I, 45 so as to hold the jaws more firmly upon the pipe or nut, and it will be seen that as the dog 20 normally forces the jaw-piece I away from the handle-bar A this will cause the jaws to open, so as to permit of a fresh adjustment 50 of the wrench whenever the handle-bar is released from pressure.

The handle-bar A ends below the shoulder 11 in a tang 10 of a somewhat flattened form, and on the shoulder fits a collar 25, formed 55 integral with which at the sides are the spring side pieces 26, bellying away from the tang at the center, such collar and side pieces being usually formed of metal somewhat resili- 60 ent, and the end of the tang when the collar is in position extending slightly beyond such side pieces, as shown, which are of the same thickness as such tang in its narrowest dimension.

When the parts are assembled, the main 65 portion of the tang and the edges of the side pieces 26 are concealed from view by handle-pieces 27, usually of wood provided with a

chamfer at one end to fit into the collar 25, two inside tongues 28 to fit down into the spaces between the edges of the tang 10 and 70 the side pieces 26, and also with an end chamfer 29, over which and the chamfered ends of the side pieces 26 fits the conical metallic securing-thimble 30, which after being firmly driven home is secured in position by a pin 75 31, driven through the same and through the tang 10, as shown.

When the wrench is to be used, the worm thumb-nut D is thrown out of engagement with the rack on the bar A into the position 80 shown in dotted lines in Fig. 1, when the slide piece or sleeve 14 may be freely reciprocated, the toothed dog 20 when the jaw-piece I is allowed to fall by gravity fully away from the bar A being out of engagement with the tooth-rack of such jaw-piece, the opening of the jaws being in this manner set approximately to the size of the nut or pipe to be rotated. The thumb worm-nut D is swung back into engagement with the rack 90 of the handle-bar A, as shown in full lines in Fig. 1, and by rotation of such nut the jaws are tightened upon such nut or pipe, when by then drawing forward upon the handle the toothed dog 20 will be forced back against 95 the toothed rack of the jaw-pieces I, and as it is forced farther back the consequent tighter gripping of the nut or pipe caused by the changing angle of the jaws by the rocking of the jaw-piece on the pivot-joint 18 will give 100 a firm hold of the device upon such nut or pipe.

Having now described my said invention, what I claim, and desire to secure by Letters Patent, is—

1. In a device of the class described, the combination with a handle-piece forming a combined slide-bar and handle and provided with a jaw-head and with a screw-thread rack on the edge, of a slide piece or sleeve reciprocating on the bar, a jaw-piece pivotally secured to the sliding sleeve so as to be incapable of more than a slight rocking movement, a worm thumb-nut revolvably mounted upon a shaft pivoted to the sliding sleeve, a 110 spring-catch for the free end of the pivoted shaft carried by the sleeve, rack-teeth much finer than the screw-rack formed on the edge of the bar of the jaw-piece facing the handle-bar, a dog having a working face provided 115 with similar coacting teeth carried by the jaw-head of the handle-bar, and a spring for normally forcing the dog toward the jaw-piece, substantially as shown and described.

2. In a device of the class described, the 120 combination with a handle-piece forming a combined slide-bar and handle and provided with a jaw-head and with a screw-thread rack on one edge, of a slide piece or sleeve reciprocating on the bar, a jaw-piece pivotally secured to the sliding sleeve so as to be incapable of more than a slight rocking movement on such pivot, a worm thumb-nut revolvably mounted upon a shaft pivoted to the 130

sliding sleeve, a catch for locking the free end of the shaft to the sliding sleeve, rack-teeth much finer than the screw-thread rack of the handle-bar formed on the edge of the bar of the 5 jaw-piece facing the handle-bar, a dog having a working face provided with similar coacting teeth carried by the jaw-head of the handle-bar, and a spring for normally forcing the dog toward the jaw-piece, and side 10 cheek-lugs extending from the jaw-head over the dog and back over the bar of the jaw-piece so as to prevent side strain upon the pivot thereof, substantially as shown and described.

15 3. In a device of the class described, the combination with a handle-bar, of a slide-sleeve reciprocating thereon, a jaw-piece pivoted to the slide-sleeve, a jaw-head carried by the handle-bar, a dog reciprocating in the 20 jaw-head of the handle-bar provided with fine serrations or teeth, adapted to coact with similar oppositely-faced teeth formed on the abutting edge of the bar of the pivoted jaw-piece when in contact therewith, means for 25 normally forcing the dog toward the jaw-piece, and means for locking the sleeve upon the handle-bar, substantially as shown and described.

4. In a device of the class described, the 30 combination with a handle-bar of a shoulder rigidly secured thereon, a tang extending beyond the shoulder, a collar secured upon the

shoulder, side pieces formed integral with the collar extending nearly to the end of the tang and bellying away from the tang at the 35 center, two handle-pieces chamfered at the ends and provided on the inner side with tongues or projections adapted to fit into the spaces between the bellied portions of the side pieces of the collar and the tang, a thimble fitting over the ends of the tang, side 40 pieces and handle-pieces, and means for securing such thimble to the tang so as to hold all such parts in position, substantially as shown and described. 45

5. In a device of the class described, the combination with a handle-bar, of a slide-sleeve reciprocating thereon, a jaw-piece pivoted to the slide-sleeve, a jaw-head carried by the handle-bar, means for locking the sleeve 50 upon the handle-bar, and a spring-plunger adapted to contact with the jaw-piece carried by the jaw-head of the handle-bar, and spring means normally preventing contact of the jaw-piece with the rear edge of the 55 handle-bar at the upper end, substantially as shown and described.

In testimony whereof I have affixed my name to the present specification in the presence of two witnesses.

DAVID STEWART.
